ROLL PAPER HOLDER AND CUTTER

Edward Waltz, Grand Rapids, Mich., assignor to The E. O. Bulman Manufacturing Company, Inc., Grand Rapids, Mich., a corporation of Michigan

Application May 27, 1953, Serial No. 357,817

4 Claims. (Cl. 242—55.5)

This invention relates to a roll paper holder and cutter for the purpose of holding a roll of wrapping paper or the like from which pieces may be unrolled and severed.

This device will operate successfully with most kinds of wrapping paper, but it is particularly intended to operate with a thin plastic material which is very hard to handle. This material is a very thin unporous sheet. While it is rather tough and does not tear easily, it is extremely susceptible to magnetism caused by static electricity, and although it has no adhesive on its surface it has an extreme tendency to cling to anything with which it comes in contact, and because of said magnetism it will sway and cling to adjacent objects.

For the foregoing reasons that part of the sheet which is unwound from the roll must be kept under control at all times.

The common use of this device is to unwind and cut off sections of the material which are laid flat on a table and in which articles are then wrapped. For this purpose the holder and cutter is designed to be placed on said table and the section which is withdrawn from the roll passes over a serrated edged tearer or cutter and is pulled downwardly over the cutting edge, where it is severed and the cut off section is in a position to be laid down on the table without moving it any great distance or changing its position.

The invention is hereafter more fully described, reference being had to the accompanying drawings in which:

Fig. 1 is a vertical section on the line 1—1 of Fig. 4.

Fig. 2 is a similar section with a part broken away showing the moving parts in a changed position,

Fig. 3 is a perspective view of the device,

Fig. 4 is a longitudinal vertical section, with parts broken away, on the line 4—4 of Fig. 1, and

Fig. 5 is a fragmentary section showing the mounting for the paper roll.

Like numbers refer to like parts in all of the figures. The device has a main body of substantially pan shape, having a bottom 1, ends 2, a back 3, and a front 4. The top of the body is partially closed by a cover 5 hinged to the back at 6. The roll of paper 7 is hung in the rear part of the body under the cover 5 in a conventional way such as by sockets 8 attached to the inner sides of the ends 2 which receive the ends of a rod 9 extending through a spool 10 on which the roll of paper is wound. The un wound portion of paper is indicated as 7a.

A vertical partition 11 is located in the body rearwardly of the front 4 and is preferably attached to or integral with the front side of the cover 5. This partition 11 terminates above the bottom 1 and may have a roller 12 at its lower edge, although such roller is not necessary. For access to the paper roll 7 for removal or replacement the cover 5 and its attached partition 11 are swung upwardly about the hinge 6 which opens up the whole interior of the body.

A swinging plate 13 is located in the body in the space between the partition 11 and the front 4. This plate is pivoted on a rod 14 near its lower edge and close to the

2

bottom 1. The upper part of the plate 13 will swing between the partition 11 and the front 4 and its upper part is shaped to lie parallel with the partition 11 when they are adjacent each other. A coil spring 15 of light tension is located around the rod 14 and its respective ends engage the plate 13 and the bottom 1 and acts to move the upper part of the plate toward the partition 11.

The unwound section of paper 7a extends from the roll 7 under the roller 12, or in the absence of such roller it extends under the lower edge of the partition 11 and thence upwardly in front of the partition and back of the plate 13, the upper part of which is urged by the spring 15 to engage the paper and grip it against the partition.

The cover 5 at its front edge has one or more finger openings 16 which merge into extensions thereof at the upper part of the partition 11 and the top of the plate 13 has corresponding openings 17 which register with the openings 16 thus exposing the upper edge of the paper 7a which is gripped between the plate and partition.

In operation, the operator grasps the upper edge of the paper which is exposed through the finger openings 16 and 17 and pulls it forwardly across the top edge of the front 4 which is provided with a serrated or sharp-edged cutting bar 18 which may be removably attached for replacement.

20 This forward movement of the paper section 7a swings the plate 13 forwardly with its top edge located below the cutting bar 18 as shown in Fig. 2. The paper is then pulled out unwinding from the roll 7 until the desired length lies forward of the cutter bar and then by a downward movement the section is torn off over the sharp edge thereof and laid down on the table forward of the holder, where it will lie smooth to be wrapped around an article.

25 Upon severing of the section of paper the remaining portion 7a is released and the plate 13, urged by the spring 15 carries it back against the partition 11 where its upper edge is gripped as previously described, with said upper edge available through the finger holes 16 and 17 for a repeated operation.

30 The plate 13 must have a substantial area because of the flimsy nature of the paper it is intended to handle. In practice, the plate has an area substantially as great as the portion of the paper which lies outside the wall 11.

35 By this means the paper, and especially the thin, flimsy, plastic type described, is kept under control at all times. The torn off section is in substantially horizontal position when severed and close to the table on which it is laid flat. The remaining portion of the paper is immediately swung back by movement of the plate 13 in a smooth, uncrumpled condition and gripped to hold it so and the finger openings, across which the paper extends, make it available to be grasped again.

40 The invention is defined by the appended claims, which 45 are to be considered comprehensive of all forms coming within their scope.

I claim:

45 1. A device of the class described, comprising a body adapted to receive and rotatably hold a roll of paper, a wall in said body adjacent said roll of paper, a cutting bar on said body and spaced from said wall, a flat plate swingably mounted in said body between said wall and said cutting bar, and spring means to swing said plate toward said wall, whereby paper unwound from said roll 50 will pass around an edge of said wall and lie clamped between said wall and said plate, said plate having an area equal to a considerable part of the area of said wall.

55 2. A device of the class described comprising an open-topped body, means for rotatably supporting a roll of paper in said body, a cover hinged to said body and partially covering the top thereof, a wall in said body connected with said cover, a cutting bar on said body spaced

from said cover and said wall, a flat plate swingably mounted in said body to swing between said wall and said cutting bar, and a spring acting to swing said plate toward said wall, said plate having an area equal to a considerable part of the area of said wall.

3. A device of the class described comprising means for rotatably holding a roll of paper, a cutting bar, a stationary wall between the roll holder and the cutting bar, a movable flat clamp member located between the stationary wall and the cutting bar, and tension means acting to move said clamp member against a section of paper located against the stationary wall, said tension means releasing said clamp member under normal pulling strain exerted on said paper, said clamp having an area equal to a considerable part of the area of said wall.

4. A device of the class described comprising, a body adapted to receive and rotatably hold a roll of paper, a stationary wall in said body adjacent said roll of paper, a stationary member located under said wall around which the paper

from the roll is drawn, a cutting bar on said body spaced from said wall, a plate swingably mounted in said body between said cutting bar and said wall and having its pivot adjacent said stationary member, whereby paper from said roll passes under said stationary member and thence upward between said wall and said swinging plate, and spring means acting to swing said plate toward said wall, said plate having a portion of its surface acting in clamping engagement with said paper against said wall, said plate having an area equal to a considerable part of the area of said wall.
